UNITED STATES PATENT OFFICE

ALBERT VUILLEMIER, OF BRISTOL, CONNECTICUT, ASSIGNOR TO THE NEW DEPARTURE MANUFACTURING COMPANY, OF BRISTOL, CONNECTICUT, A CORPORATION OF CONNECTICUT

METHOD OF FEEDING ARTICLES TO GRINDING MACHINES

Application filed April 4, 1929. Serial No. 352,460.

This invention relates to a method of feeding articles to grinding machines and comprises all the aspects of novelty herein disclosed in connection with a method of feeding balls to a centerless grinding machine having grooved wheels. 55

In a prior centerless grinding machine for grinding balls between grooved wheels, it has been proposed to feed the balls intermittently in a straight line along a work support from one set of ball grooves to another, one of the opposed wheels being moved intermittently away from the other to let the balls pass the ribs separating the grooves. This movement of the wheel has heretofore seemed necessary although it leads to complications and expensive mechanism and the wheels must be arranged side by side. An object of the invention is to provide an improved method of feeding articles to centerless grinding machines, such that the above mentioned and other disadvantages can be overcome. Another object is to provide a method of feeding balls from groove to groove of opposed wheels which revolve on normally stationary axes. To these ends and to improve generally and in detail upon methods of this character, the invention further consists in the various matters hereinafter described and claimed.

In its broader aspects, the invention is not necessarily limited to the particular steps selected for illustration in the accompanying drawings in which

Fig. 1 is an end view, with parts in section, of apparatus for carrying out the method, the articles being in grinding position.

Fig. 2 is a similar view, the articles being in feeding position.

Fig. 3 is a left side view of the apparatus, the articles being in a slightly different feeding position.

Fig. 4 is a plan view of the lower wheel and feed mechanism, the articles being in grinding position.

The preferred steps of the method consist in moving the articles transversely of the wheels into the mating grooves at the grinding throat for grinding, afterwards moving the articles transversely out of the grooves,

advancing them longitudinally at one side of the grinding throat until they are in line with other grooves, and moving them transversely again into such grooves for further grinding, a new article being fed in and a finished article being removed at every such longitudinal advance.

In the drawings, the numeral 10 indicates a grinding wheel rotatable at high speed and preferably arranged above an opposed slowly rotatable regulating wheel 12 to form a grinding throat between them. When grinding balls, the wheels have sets of mating grooves 14 conforming to the balls and the wheels preferably have their axes parallel. 65 Each ball is ground a little in each pair of mating grooves and its transfer from one pair of grooves to another is sufficient to insure a changing axis of rotation for producing a true spherical shape. When in grinding position, each ball or other article is supported by one of the wheels and held in the grinding throat from movement other than rotation by a pair of aligned rods 16, each 70 adjustably and removably fastened by a set 75 screw 18 to a yoke 20 which surrounds the grinding throat. The rods may be provided with hardened tips to engage the articles. The yoke is slidable transversely of the wheels by any suitable mechanism to carry 80 the balls into or out of the grinding throat.

When the balls are out of the grinding throat, they are supported on a longitudinally reciprocable slide 22 having ball grooves 24 which are preferably spaced apart the same distance as the wheel grooves and located in alignment with the wheel grooves. A short rearward sliding of the slide 22, will thus move each ball from transverse alignment with one pair of wheel grooves into 85 transverse alignment with a succeeding pair of wheel grooves, each ball of course being free to move longitudinally of the wheels with the slide from between one pair of rods 16 to the next pair. Whenever the balls are 90 moved transversely between the wheels by the yoke 20 and rods 16, they roll out of the grooves of the slide 22 into the wheel grooves 14 and the empty slide 22 then moves forwardly, its first groove, as indicated in Figs. 100

2 and 4, being carried under a suitable supply pipe 26 at one end of the wheels to receive a new ball. The empty slide is then ready to receive the balls rolled out of the grinding 5 throat and advance all of them, including the new ball, after the yoke 20 slides outwardly again. Whenever the slide 22 thus moves rearwardly, to the position shown in Fig. 3, the balls in the supply pipe 26 may be retained 10 by an ungrooved extension at the front end of the slide 22 and a finished ball in the rear groove 24 of the slide is ready for removal beyond the rear ends of the wheels as by an extra rod 28.

15 The location of the feed supply pipe beyond the ends of the wheels is not essential because an article may be fed directly onto the slide between the ends of the first pair of rods. A feed slide may be desirable at each 20 side of the grinding throat with the yoke 20 slidable from a middle position to both sides alternately and with one or more sources of supply. It is also within the province of the invention to secure self dressing of the wheels 25 by grinding in the odd and even grooves alternately. It is not essential to have the wheels arranged one over the other although this is preferred to save floor space and for other reasons, such as to get better control of 30 rotation of a round article.

I claim:

1. The method of feeding articles to a grinding machine having a grooved wheel peripherally opposed to a second grooved wheel 35 to form a grinding throat between them, which consists in moving an article transversely of the wheels into a groove at the grinding throat, holding the article from movement other than rotation in the groove 40 for grinding, moving the article transversely out of the grinding throat while maintaining the grooved surfaces of the wheels in a constant spaced relation, and moving a second article transversely of the wheels into 45 said groove; substantially as described.

2. The method of feeding articles to a grinding machine having a grooved wheel peripherally opposed to a second wheel to form a grinding throat between them, which consists in moving an article transversely of the 50 wheels into one of the grooves at the grinding throat, holding the article in the groove for grinding, moving the article transversely out of the grinding throat, moving the article 55 into another groove for further grinding and simultaneously moving another article transversely of the wheels into the first groove; substantially as described.

3. The method of feeding articles to a 60 grinding machine having a grooved wheel peripherally opposed to a second wheel to form a grinding throat between them, which consists in moving an article lengthwise of the wheels from a position beyond one end 65 of the wheels to a position in line with a wheel

groove, and moving the article transversely of the wheels into the groove at the grinding throat; substantially as described.

4. The method of feeding articles to a grinding machine having a grooved wheel peripherally opposed to a second wheel to form a grinding throat between them, which consists in moving an article transversely of the wheels into a groove at the grinding throat, holding the article in the groove for grinding, 70 moving the article transversely out of the grinding throat, moving the article lengthwise of the wheels to a position beyond the ends of the wheels, and moving another article transversely of the wheels into the 75 groove; substantially as described.

5. The method of feeding articles to a grinding machine having a grooved wheel peripherally opposed to a second wheel to 80 form a grinding throat between them, which consists in moving an article transversely of the wheels into one of the grooves at the grinding throat, holding the article in the groove for grinding, moving the article transversely out of the grinding throat, moving the article lengthwise of the wheels to a 85 position in line with another wheel groove, and again moving the article transversely into said other groove for further grinding; substantially as described.

6. The method of feeding articles to a grinding machine having a grooved wheel peripherally opposed to a second wheel to 90 form a grinding throat between them, which consists in moving an article transversely of the wheels into one of the grooves at the grinding throat, holding the article in the groove for grinding, moving the article transversely out of the grinding throat, moving the article lengthwise of the wheels to a 95 position in line with another wheel groove, again moving the article transversely into said other groove for further grinding, and simultaneously moving another article transversely of the wheels into the first groove; 100 substantially as described.

7. The method of feeding articles to a grinding machine having a grooved wheel peripherally opposed to a second wheel to 115 form a grinding throat between them, which consists in moving an article lengthwise of the wheels at one side of the grinding throat to a position in line with one of the wheel grooves, then moving the article transversely into the groove at the grinding throat, holding the article in the groove for grinding, moving the article transversely out of the grinding throat, again moving the article lengthwise of the wheels to a position in line with another wheel groove, and again moving the article transversely into said other groove for further grinding; substantially as described.

8. The method of feeding articles to a grinding machine having a grooved wheel periph- 125

erally opposed to a second wheel to form a grinding throat between them, which consists in moving an article lengthwise of the wheels at one side of the grinding throat to a position in line with one of the wheel grooves, then moving the article transversely into the groove at the grinding throat, holding the article in the groove for grinding, moving the article transversely out of the grinding throat, again moving the article lengthwise of the wheels to a position in line with another wheel groove while moving a second article into line with the first groove, and again moving the first article transversely into said other groove for further grinding while moving the second article into the first groove; substantially as described.

9. The method of feeding balls to a grinding machine having a grooved wheel peripherally opposed to a second grooved wheel to form a grinding throat between them, which consists in rolling a ball transversely of the wheels into mating grooves of the wheels, holding the ball for rotation in the grooves for grinding, and rolling the ball transversely out of the grooves; substantially as described.

10. The method of feeding balls to a grinding machine having a grooved wheel peripherally opposed to a second grooved wheel to form a grinding throat between them, which consists in rolling a ball transversely of the wheels into mating grooves of the wheels, holding the ball for rotation in the grooves for grinding, rolling the ball transversely out of the grooves, sliding the ball longitudinally of the wheels, and rolling it transversely into another pair of mating grooves for further grinding; substantially as described.

40 11. The method of feeding articles to a grinding machine having a grooved grinding wheel peripherally opposed to a regulating wheel to form a grinding throat between them, which consists in moving the article transversely of the wheels into the grinding throat, supporting the article on one of the wheels for rotation during grinding, and holding the article from all movement except rotation during said grinding; substantially as described.

50 12. The method of feeding articles from groove to groove of a pair of peripherally opposed wheels, which consists in maintaining the grooved surfaces of the wheels in constant spaced relation to preserve the width of the grinding throat between them, and moving an article out of the grinding throat to pass it around the rib which separates one groove from another; substantially as described.

60 In testimony whereof I hereunto affix my signature.

ALBERT VUILLEUMIER.
